Attorney.

UNITED STATES PATENT OFFICE

JOSEPH ALFRED MILLS, OF EAST KIRKBY, ENGLAND

MANUFACTURE OF KNITTED GARMENTS OR FABRICS ON CIRCULAR-KNITTING MACHINES

Application filed November 20, 1928, Serial No. 320,676, and in Great Britain November 26, 1927.

This invention relates to improvements in the manufacture of knitted garments or fabrics, on circular knitting machines which are provided with facilities for fashioning the same, that is, varying the diameter by varying the number of vertical wales from time to time in the work as the latter is produced. Such machines are as described in my United States Patent No. 1,608,989, provided in addition to the ordinary cylinder needles, with a number of supplementary needles which are therein termed fashioning needles.

These supplementary needles are disposed in an exterior bed disposed at right angles to the axis of the needle cylinder, and are not only adapted to draw their loops in the same direction as the cylinder needles, but can be put into and out of action as required.

When these supplementary needles are withdrawn out of action, they in the ordinary course, immediately transfer their loops to the adjacent cylinder needles, in order to obviate dropped loops and faults in the work.

According to this invention, improved results are obtained when fashioning, by suspending the transfer of the loop on a withdrawn supplementary needle, until one or more further courses have been knitted, and other effects are obtained, by suspending a series of loops for one or more courses, that is, withdrawing a series of the supplementary needles out of action for a predetermined number of courses, during which period they retain their loops, and subsequently bringing them into action again, either after transferring their loops or without transferring their loops.

Referring to the accompanying drawing.

Fig. 1 is a diagram showing the disposition of the withdrawn and transferred loops in a knitted garment or fabric when fashioned according to my invention.

When fashioning a seamless garment or tubular fabric for instance, the loops on the supplementary needle when they are with-

drawn out of action, are not transferred to adjacent cylinder needles immediately, but are suspended whilst another course is knitted on the latter, and are then transferred. The point in the fabric where the vertical wale knitted by any of the said supplementary needles, is thus suppressed, is not with this method so noticeable, as when the transfer of the loops is effected immediately as is usual.

The position of a loop which is withdrawn, suspended, and subsequently transferred as described, is indicated in Fig. 1, in which A is the withdrawn and suspended loop in the vertical wale B produced by a supplementary needle, said wale B being shaded in the drawing so as to distinguish it from the rest. The withdrawn loop A it will be seen, is suspended whilst the next course C is knitted, and is then transferred from the supplementary needle to the adjacent cylinder needle on its left, and knitted into the following course D as shown in the drawing.

The point where the vertical wale B is suppressed, is with this method, only discerned with difficulty in the knitted fabric.

What I claim is:

1. The method of shaping a fabric, which consists in narrowing the fabric by holding the supplementary or fashioning needles out of action with the loops retained thereon whilst a course is knitted on the remaining needles, then transferring the loop from the supplementary or fashioning needle to the next adjacent needle and knitting the transferred loop together with the loop already thereon into the next following ordinary course, that is, the next course but one to that from which the loop was withdrawn.

2. A knitted fashioned fabric formed of successive courses of stitches comprising wales certain of which are formed of plain stitches and draw stitches, each draw stitch being knitted into an adjacent wale of the next course but one from the course from
